UNITED STATES PATENT OFFICE

THOMAS MOORE, OF KEWANEE, ILLINOIS

TENSION ROLL

Application filed July 30, 1927. Serial No. 209,585.

The invention relates broadly to tensioning devices, and particularly to a tensioning device adapted to be attached to a computing machine for preventing its roll of paper from acquiring slack, by said tensioning device exerting pressure on said roll to increase the tension on the paper during an unwinding operation.

An object of the invention is to provide means adapted to be attached to a computing machine, to engage its paper roll to prevent it from unduly unwinding by inertia during the operation of the machine.

Another object of the invention is to provide a tensioning device that may be readily attached to a computing machine and which is arranged for easy adjustment thereon.

Another object of the invention is to provide a tensioning device in which gravity controlled means is provided to automatically engage the roll of paper.

Another object of the invention is to provide means on the tensioning device to prevent axial displacement of the paper roll thereon.

In general it is intended to provide a tensioning device adapted to be supplied as an accessory to, or standard equipment for a computing machine, which is easily adjustable, adapted to being mounted on a machine and arranged for gravity controlled adjustment with the paper roll, to prevent the roll from unduly unwinding and forming a slack, as well as being arranged to prevent axial displacement of the paper roll with respect to its proper position on the machine.

With the foregoing and such other objects in view as will appear as the description proceeds, the invention resides in the combination and arrangement of the parts and in the details of construction hereinafter described and claimed, it being understood that changes in the precise embodiment herein described, may be made within the scope of what is claimed without departing from the spirit of the invention.

In the drawings:

Fig. 1 is a fragmentary side elevation of a computing machine shown with a preferred

form of the device attached thereto in operative position.

Fig. 2 is a plan view of the same.

Fig. 3 is a perspective view of a frame carrying a roller showing a fragment of the means for securing it to the machine.

Fig. 4 is a perspective view of another form of the tensioning device.

Fig. 5 is an enlarged sectional view showing a portion of the frame and its adjusting and leveling means.

The computing machine as a whole is designated by 11 and has secured to its ends side brackets 12 and 13, in this instance by means of machine screws 14, but said brackets may be secured in any appropriate manner. The ends of these brackets terminate in arms and are provided with aligned bores to carry a cross shaft 15, on which a roll of paper 16 is rotatably mounted, its end being adapted to slide through guide-ways 17, formed in the machine, and around the roll 18 through the path of means provided for printing thereon.

The tensioning device comprises a frame formed by spaced side walls 19 held in spaced relationship by means of guides or spacers 21 pivotally secured thereto, by pins 22, or by turned down portions of the spacer ends.

A finger 23 is formed integral with each side wall and extends downwardly substantially in alignment with the pivotal pins of an eccentrically mounted roller 24, to form means to engage the sides of the paper roll to prevent axial displacement thereof during the operation of the device.

The means for securing this frame suspended over the paper roller comprises a standard 25 having a cross bar or arm 26 extending at right angles therefrom over the paper roll 16 to which the frame is secured in any approved manner, but as illustrated the arm 26 is secured thereto by means of tongues engaging slots in the side walls 19.

The other end of the standard is provided with a slotted opening through which a thumb screw 27 extends to threadingly engage a tapped opening in the arm 13 to hold the device in the desired adjusted position.

It will be apparent that the roller 24 normally drops into engagement with the paper

roll by gravity, and that it will remain in engagement with the paper roll after a considerable amount of the paper has been unwound, and the degree to which the paper may be unwound before the roller 24 fails to engage and has to be reset depends upon the eccentricity of the roller. To reset the roller it is only necessary to loosen the thumb screw 27 and lower the frame. The roller 24 is 10 preferably of sufficient weight to exert the proper amount of pressure on the paper roll to prevent said roll from inadvertently unwinding in a clock-wise direction. When it is desired to prevent unwinding of the paper roll, the roller 24 is reversed about its pivot and disposed on the opposite side thereof so as to cause same to wedge or bind on the paper roll upon clock-wise rotation.

The modified form of the invention, shown 20 in Figures 4 and 5 comprises a frame 29 of any suitable form, preferably comprising a pair of parallel spaced side walls connected on their ends by transverse members in which a roller 31 is rotatably mounted and may be 25 either mounted concentrically or eccentrically, but as here shown it is mounted concentrically.

Lugs 32 extend upwardly from each corner of the frame and are provided with apertures 30 in which adjusting means, such as screw eyes 33, are inserted and each provided with a nut 34.

Flexible elements 35 extend from these screw eyes to the arm 26^a of the securing 35 means, to which they are affixed. It will be obvious that the tensioning device may be adjusted by taking up or letting out the flexible means, or the device as a whole may be leveled by adjusting one or more of the nuts 34.

40 In other respects the device is similar to the preferred form.

It is not intended to be limited to the exact details shown and described except in so far as limited by the claims.

45 I claim:

1. In a device of the class described adapted 50 to be attached to a computing machine having a roll of paper mounted for rotation therein, means for securing said device to said machine, a substantially rectangular frame attached to said securing means, means on said frame for guiding said paper from said roll, and a roller eccentrically mounted in said frame engaging said roll of paper.

55 2. In a device of the class described adapted to be attached to a computing machine having a roll of paper mounted for unwinding therefrom, adjustable means for securing 60 said device to said machine, a frame suspended from said securing means comprising spaced walls, guiding means for the paper extending below said walls and a roller eccentrically mounted between said side walls, said roller being adapted to engage said roll

of paper to prevent unintended unwinding thereof.

3. In a device of the class described adapted 70 to be attached to a computing machine having a roll of paper mounted for unwinding therefrom, means for adjustably securing 75 said device to said machine, a frame suspended from said securing means comprising spaced walls having integral extensions forming fingers to engage the ends of the roll to prevent axial displacement thereof, and a roller eccentrically mounted in said side walls, said roller being adapted to engage said roll of paper to prevent unintended unwinding thereof.

80 In testimony whereof I affix my signature at Kewanee, Illinois.

THOMAS MOORE.
